United States Patent Office

Des. 219,279
Patented Nov. 24, 1970

219,279

DESK UNIT

Jack L. Beavers, Boulder, Colo., assignor to Design Products, Inc., Boulder, Colo., a corporation of Colorado

Filed Oct. 22, 1969, Ser. No. 19,667

Term of patent 14 years

Int. Cl. D6—01

U.S. Cl. D33—7

FIG. 1

FIG. 2

FIG. 3

FIG. 4

FIG. 5

FIG. 6

FIG. 7

FIG. 8

FIG. 1 is a rear perspective view of a desk unit illustrating my new design;

FIG. 2 is a front perspective view of the desk unit;

FIG. 3 is another front perspective view thereof;

FIG. 4 is a top plan view;

FIG. 5 is a rear elevational view;

FIG. 6 is a front elevational view;

FIG. 7 is a side elevational view; and

FIG. 8 is another side view.

I claim:

The ornamental design for a desk unit, as shown.
